UNITED STATES PATENT OFFICE

103,423

DESIGN FOR TEXTILE FABRIC

Curt Erwin Forstmann, Montclair, N. J.

Application May 18, 1935, Serial No. 56,904

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, Figure 1 is a plan view of a piece of the textile fabric embodying the design of the present invention, the cloth depicted is of a single color.

Figure 2 is a fragmentary plan view on a slightly enlarged scale illustrating the structure of the design stripe.

The design motif comprises spaced parallel diagonal stripes, each composed of long and short diagonal dashes in alternate arrangement being distinguished from the background by physical characteristics of the yarn other than color.

I claim:

The ornamental design for textile fabric as described and shown.

CURT ERWIN FORSTMANN.
